UNITED STATES PATENT OFFICE.

EDWARD A. HAMILTON, OF HAWTHORNE, PENNSYLVANIA.

POT-MAKING MACHINE.

1,267,215.

Specification of Letters Patent. Patented May 21, 1918.

Application filed June 29, 1916. Serial No. 106,671.

To all whom it may concern:

Be it known that EDWARD A. HAMILTON, a citizen of the United States, residing at Hawthorne, in the county of Clarion and State of Pennsylvania, have invented new and useful Improvements in Pot-Making Machines, of which the following is a specification.

This invention relates to the manufacture 10 of hollow clay ware and particularly to pots used in chemical and metallurgical operations. Such pots are usually formed with rounded or substantially hemi-spherical bottoms. Considerable difficulty has been here- 15 tofore experienced in forming a pot with a rounded bottom the walls of which are sub- stantially the same thickness as the walls of the pot.

A better product seems to be provided by 20 rolling the clay in the matrix or forming die than in a construction of machine in which the clay is simply "plastered against the side wall of the die."

In carrying out my invention I prefer to 25 form the side walls of the pot by rolling, as for example with a roll. The pot thus formed is provided with a relatively thick bottom and after the roll is taken out the superfluous clay is removed from the bottom 30 so that the entire wall of the pot except the bottom is of uniform thickness.

For the purpose of illustration I have 35 shown certain mechanism capable of being employed in carrying out the spirit of my invention although I desire not to be limited to the particular form illustrated.

In the drawings:—

Figure 1, is a view of a machine for carrying out my invention parts being shown in 40 section and parts in elevation.

Fig. 2, is a plan view of a leather strip used in connection with my invention and,

Fig. 3, is a plan view of a smoothing roller.

45 Referring now to the drawings by numerals of reference 1, designates a standard upon which is a sleeve 2, carrying a sectional arm 3 which is connected to a counter-balance by the flexible connection 5, which 50 passes over the superimposed pulleys 6 and 7. The sectional arm 3 is provided with an extension 8, held to the arm proper by a bolt 9 and said arm may be steadied in the slot 10 on the standard 11 by the connection 12. 55 On the outer end of the extension 8 is a bearing 13 in which is a shaft 14 adapted to be

rotated by a wheel 15. On the lower end of the shaft 14 is an eccentric 16 carrying an inclined shaft 17 on which is mounted a roller 18. 19 is a matrix or die mounted upon a hollow shaft 20 in which is a plunger 21 for dislodging the bat. Thus far the described device is known as the Weeks machine and its mode of operation is well known to those skilled in the art.

60 This type of machine however has been used to make flat bottom pots and in so far as I am aware it has not been successfully employed for the purpose of making round bottom pots nor indeed am I aware that my 70 invention has been used in any machine for round bottom pots.

In carrying out my invention I prefer to 75 construct a concave bat 22, of a series of strips or segments for the purpose of preventing warping and to construct the bat with a shoulder 23 whereby it may be easily moved from the matrix. It will be observed that the concave portion 24 is slightly less in diameter than the outer diameter of the 80 bat. The ideal construction of the bat would be to run the concave portion up to a sharp point but in actual practice the edge of the bat would become broken or chipped and soon become unfit for use. I have therefore 85 provided a removable bead and edge ring 25 which may consist of a flexible strip as

for example leather, provided with an inner curved surface conforming with the inner surface of the bat and having a shoulder 26 90 whereby the lower portion of the strip can overlap the edge of the bat thereby being securely held between the lower wall of the bat and the inner wall of the matrix. The arrangement of the bat and flexible matrix 95 provides a symmetrical contour for the bottom of the pot 27. If desired the strip 25 may be omitted and the superfluous clay ad-

hering to the outside of the wall may be scraped away. 28 is a standard adjacent to 100 the matrix on which is a universal joint 29 carrying a lever 30 on which is a roll 31. The lever is provided with holds 32 and 33. The universal joint will permit the roller to be inclined at any desired angle to work the 105 clay into the proper shape to form the top of the pot. 34 is a standard on which is a sleeve 35 carrying an arm 36. The arm 36 is connected to the counter-balance weight by the cable 38 trained around the pulleys 39 and 40. On the outer edge of the arm 36 110 is a threaded rod 41 carrying a cutter blade

42 curved to conform to the inner contour of the pot 27. The rod 41 may be fed in its bearing by the hand wheel 43.

When the parts are assembled the clay is first placed in the matrix and the roll 18 is caused to assume a relatively proper position toward the shaft 20 and thereby the matrix. The pot will be made in substantially the well known manner incident to the 10 Weeks machine. The bottom however will be considerably thicker than the walls. After this has taken place the roll 18 will be removed and the cutter 42 will be moved around into position and inserted into the 15 pot.

During the formation of the pot the roller 31 will be manipulated to form the upper edge of the pot in the proper manner. After the pot is formed the power will be imparted to the plunger 21 so as to raise the pot slightly above the matrix and then be removed to be subjected to the finishing process.

A pot formed according to the manner 25 herein described will possess considerable strength over a pot formed in an ordinary plaster mold for the reason that the clay can be worked most advantageously and a relatively small per cent. of water will be 30 used.

According to my invention the rounded bottom pot will possess all the mixtures of the ordinary flat bottom pot subjected to 35 rolling process and it can be manufactured at substantially the same cost.

What I claim is:—

1. In a device of the class described the combination with a forming die or matrix, of a bat in the bottom of the matrix, pro-

vided with a concave portion and a forming device engaging the edge of the bat which is substantially coincident with the curvature of the concave portion of the bat. 40

2. In a device of the class described the combination with a pot forming die or matrix, of a bat upon the floor of the matrix and provided with a concave portion and a removable edge ring carried by the bat. 45

3. In a device of the class described the combination with a pot forming die or matrix, of a bat upon the floor of the matrix and provided with a concave portion and a removable edge ring having a portion to overlap the outer wall of the bat and a shoulder seated upon the upper edge of said 50 bat. 55

4. In a device of the class described the combination of a pot forming die or matrix, a removable bat upon the floor of said matrix provided with a concave portion, a flexible ring resting upon the edge of said bat and having an inner face curved on substantially the same arc as that of the concave portion of the bat. 60

5. In a device of the class described, in combination with a matrix, a bat mounted in and of a less diameter than the body and a ring shaped to slide within the matrix and embracing the upper edge portion of the bat whereby the bat may be centrally located in 70 the matrix. 65

In testimony whereof I affix my signature in presence of two witnesses.

EDWARD A. HAMILTON.
